UNITED STATES PATENT OFFICE.

WILLIAM LOACH, OF OSHAWA, ONTARIO, CANADA, ASSIGNOR TO THE PEDLAR PEOPLE
LIMITED, OF OSHAWA, ONTARIO, CANADA.

METHOD OF MAKING METAL FABRIC.

1,189,369.

Specification of Letters Patent.

Patented July 4, 1916.

Application filed November 2, 1915. Serial No. 59,311.

To all whom it may concern:

Be it known that I, WILLIAM LOACH, a subject of the King of Great Britain, and resident of Oshawa, in the Province of Ontario, Dominion of Canada, have invented 5 a certain new and useful Method of Making Metal Fabric, of which the following is the specification.

This invention relates to an improved 10 method of making metal fabric, and the objects of the invention are to enable metal fabric having expanded portions with connecting strips of an improved character to be turned out rapidly and at low cost.

15 Further objects are to strengthen unexpanded connecting strips to prevent breaking of the strands at the point where the expanded portion connects with the unexpanded portion and to provide for shortening 20 of the unexpanded section to compensate with the expanded section.

According to the present invention the unexpanded portions are shortened simultaneously with the expanding of the other 25 portions and in a further operation the unexpanded portions are strengthened by up-setting corrugations formed therein.

Further features and objects of the invention will appear as the specification proceeds.

In the drawings, Figure 1 is a side elevation of a machine for performing the principal operation of the method. Fig. 2 is a front view of the same partially in section. 35 Fig. 3 is a sectional detail through a pair of dies used to finish the product. Fig. 4 is a front elevation of a set of dies for forming the ribs in the product. Fig. 5 is a front elevation of the first set of rollers. Fig. 6 is a sectional detail through the feeding rolls. Fig. 7 is a sectional detail of the feeding rolls. Fig. 8 is a plan view of the metal blank after it has received the first slitting operation. Fig. 9 is a section on the line 40 2-2 of Fig. 8. Fig. 10 is a perspective view of the product after the first step in the expansion. Fig. 11 is a plan view of the product after it has expanded and has the first rib formed therein. Fig. 12 is a section 45 through the product shown in Fig. 11. Fig. 13 is a sectional view through the final product.

In the drawings like characters of reference indicate corresponding parts in all the 50 figures.

The process uses as raw material strips of sheet metal of any desired and convenient gage, such as at present used for the manufacture of what is known as "expanded metal." These strips are first slit in the 60 usual way prior to expansion, the slitting operation being accomplished on any suitable rotary cutter or slitter, the construction of which is well known in the art, the product from such cutter or slitter as it comes 65 from these slitting rollers being shown in Figs. 10 and 11 of the drawings.

It will be seen that the strip A is formed with unslit or plain portions 10 and slit portions 11, said slit portions being designed 70 to be expanded in the manner hereinafter described.

The next operation is the expansion which is accomplished by passing the slit strip A between pairs of laterally separated 75 rollers having their peripheries radially separated.

The process may be carried out, if desired, in an organized machine or might be performed by hand. I prefer to employ 80 machinery in the performance of the process and in the accompanying drawings have illustrated machinery invented by me by the use of which the same may be performed. The said machine is not claimed 85 in this application, but is claimed in the division thereof.

The machine comprises a plurality of pairs of rotary dies B, C, D, E and F mounted on shafts 12 and 13. The shaft 13 90 is journaled in suitable bearings in the side frames G and H while the shaft 12 is journaled in suitable sliding bearings 15 which are adapted to be adjusted in position by adjusting screws 16 whereby the shaft 12 95 with the dies thereon may be adjusted to and from the shaft 13.

The dies are laterally separated from each other as indicated and one of the dies of each pair is free on the shaft; thus for 100 instance in the pair of dies B the die 17 is connected to and rotates with the shaft 12 while the die 18 is loose on the shaft 13. In the next pair the die 20 will be connected to the shaft 13 while the die 21 is loose on 105 the shaft 12. In the pair D the die 22 will rotate with the shaft 12 while the die 23 is free on the shaft 13. In the pair E the die 24 will rotate with the shaft 13 while the die 25 is free on the shaft 12. In the pair 110

F the die 26 will rotate with the shaft 12 while the die 27 is free on the shaft 13.

The shafts 12 and 13 are rotated by convenient means. As shown, a gear 28 on the shaft 13 is adapted to mesh with a pinion 29 on a counter shaft 30 journaled in the frame and carrying a gear 31 meshing with a pinion 32 on a counter shaft 33 which carries a driving pulley 34.

10 The dies are formed with intermeshing teeth adapted to form corrugations of a convenient size in the plain portions of the strips. The strip to be expanded is fed to the rotary dies from between a set of feeding rollers H' situated a distance in advance of the dies and midway between them. This set of feeding rollers includes lower rollers 35 mounted on the shaft 36 and upper adjustable rollers 37, each of said adjustable rollers being supported in a suitable yoke 39 which is adjustably connected to a cross bar 40 by means of a bolt 41 extending through a slot 42 and also by means of adjusting screws 43 extending through 20 the top of the yoke into the cross bar.

The rotary dies are laterally separated a distance which corresponds to the plain portions 10 in the strips.

As the peripheries of adjacent rollers are 30 separated from each other in a radial direction it will be seen that the portion 11 of the strips will be expanded between them to assume the formation shown in Fig. 10. At the same time corrugations will be 35 formed in the plain portions 10 which will shorten said plain portions to correspond with the lengthwise shortening which takes place in the expanded portions as they are expanded.

40 The next operation is the formation of longitudinal ribs in the corrugated portions which is accomplished by passing the strip through coöperating dies L and M mounted on shafts N and O. These dies are 45 of the form shown in Fig. 4 and are adapted to form longitudinal ribs in the corrugated portion which will serve to strengthen the same. These corrugations may be increased in successive sets of dies Q, R and 50 S, T and may be finally caused to produce the product shown in Figs. 11 and 12.

To finally finish the product, the ribs 40' appearing in the product shown in Figs. 11 and 12 are adapted to be closed somewhat 55 and to have the corrugations pressed out to a certain extent which will upset the material to increase the thickness of and strengthen the unexpanded portion. This is most conveniently accomplished in a hydraulic press by the use of dies such as shown in Fig. 3, the upper die 41' having a tongue 42' adapted to enter the lower die 43', which lower die is formed with pivoted wings 44 and 45 normally held a short distance above the base piece 46 by springs 47

and 48 and being designed to be closed down against the tongue when the die 41' moves downwardly.

In practice the die 41' will be connected to the movable part of a hydraulic press 70 and strips of the product of convenient length, say sixteen feet, will be placed in position in it and the die operated to close the rib 40' and at the same time upset the corrugations. 75

The product just described has many advantages, in particular the simultaneous shortening and expansion avoids any undue strain in the various parts of the product and the final upsetting of the corrugations 80 gives increased strength to the non-expanded portion, and in fact may be caused to increase the gage of the metal in the unexpanded portion.

It will be observed that the operation of 85 the dies draws the unslotted portions away from each other in a direction diagonal to the original plane of the sheet and while drawing them apart maintains them in substantial parallel relation to each other. By 90 reference to Fig. 6 it will be seen that alternate sections of unslotted metal are carried away from each other on opposite sides of the plane of the sheet.

As many changes could be made in the 95 above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. The herein described method of manufacturing metal fabric which comprises simultaneously expanding one portion of the fabric laterally while shortening another laterally adjacent portion of the fabric longitudinally. 105

2. The herein described method of manufacturing metal fabric which comprises slitting longitudinal strips of the same, then simultaneously expanding the slotted portions laterally while shortening the unslotted portion longitudinally. 115

3. The herein described method of manufacturing metal fabric which comprises simultaneously expanding portions of the fabric laterally while corrugating other laterally adjacent portions of the fabric longitudinally. 120

4. The herein described method of manufacturing metal fabric which comprises expanding portions of the fabric laterally while corrugating other laterally adjacent portions of the fabric longitudinally and then flattening the corrugations. 125

5. The herein described method of manufacturing metal fabric which comprises ex- 130

panding portions of the fabric and then increasing the thickness of the unexpanded portions.

6. The herein described method of manufacturing metal fabric which comprises expanding portions of the fabric and increasing the thickness of the unexpanded portions by corrugating and upsetting the metal thereof.

10 7. The herein described method of manufacturing metal fabric which comprises slitting strips of the same leaving unslit portions between and then passing the slit strips between sets of rotary dies separated laterally and having their peripheries separated radially whereby the fabric is expanded in a diagonal direction between adjacent dies.

8. The herein described method of manufacturing metal fabric which comprises first forming longitudinal slitted portions in a strip of sheet metal, then simultaneously expanding the slitted portions while corrugating the unslit portions and then forming ribs in the corrugated portions.

20 9. The herein described method of manufacturing metal fabric which comprises first forming longitudinal slitted portions in a strip of sheet metal, then simultaneously

expanding the slitted portions while corrugating the unslit portions and then forming ribs in the corrugated portions, and then flattening the corrugations.

10. The process of expanding a sheet of metal having slitted and unslit portions which consists in drawing the unslit portions as a whole apart into different planes while maintaining them in substantially parallel relation.

11. The process of expanding a sheet of metal having slitted and unslit portions which comprises drawing the unslit parts as a whole away from each other into different planes in a direction diagonal to the plane of the original sheet.

12. The process of expanding a sheet of metal having slitted and unslit portions which consists in carrying alternate sections of unslit metal as a whole away from each other into different planes on opposite sides of the plane of the sheet.

In witness whereof I have hereunto set my hand in the presence of two witnesses.

WILLIAM LOACH.
